(57) **ABSTRACT**

Derivatives of N-phenyl-3,4,5,6-tetrahydrophthalimide of formulae I and/or II

where A, R, E_n, Y, and R¹⁶ have the meanings stated in the description, which compounds are used for the dessication and abscission of plant organs.

5 Claims, No Drawings

USE OF DERIVATIVES OF N-PHENL-3,4,5,6-TETRAHYDROPHthalimide FOR THE DESICCATION AND ABSCISSION OF PLANT ORGANS

Matter enclosed in heavy brackets [ ] appears in the original patent but forms no part of this reissue specification; matter printed in *italics* indicates the additions made by reissue.

This application is a continuation of patent application Ser. No. 08/294,784, filed on Aug. 8, 1994, now abandoned, which is a continuation of patent application Ser. No. 08,115,595, filed on Sep. 3, 1993, now abandoned, which is a reissue application of U.S. Pat. No. 5,045,105.

The present invention relates to the use of derivatives of N-phenyl-3,4,5,6-tetrahydروphthalimide of the general formulae I and/or II

where

R is hydrogen, fluorine or chlorine,

A is hydrogen, C_1 - C_4 cyanoalkyl or a group I-1 to I-11

- I-1 R^1 is hydrogen, chlorine, bromine, cyano or C_1 - C_6 -alkyl,
 I-1 R^2 is hydrogen, C_1 - C_8 -alkyl, $[C_1$ - C_8 -alkenyl], C_2 - C_8 -alkenyl, C_2 - C_4 -alkynyl, C_1 - C_4 -alkoxy- C_1 - C_4 -alkyl, C_1 - C_4 -alkylthio- C_1 - C_4 -alkyl, phenyl- C_1 - C_3 -alkyl or, [where X is NR⁸] where Q is NR⁸, also C_1 - C_4 -hydroxy-alkyl, C_1 - C_4 -alkoxy, C_2 - C_4 -alkenyl, phenyl, phenyl substituted by halogen, C_1 - C_4 -alkyl or -alkoxy, C_1 - C_4 -haloalkyl or -haloalkoxy,
 I-2 R^3 is hydrogen, C_1 - C_4 -alkyl, C_1 - C_4 -hydroxyalkyl, C_1 - C_4 -haloalkyl, C_1 - C_5 -cyanoalkyl, C_1 - C_4 -mercaptoalkyl, C_1 - C_4 -alkoxyalkyl, C_1 - C_4 -alkylthioalkyl, C_1 - C_4 -alkylcarbonyloxy- C_1 - C_4 -alkyl or C_1 - C_4 -alkoxycarbonyl- C_1 - C_4 -alkylthioalkyl,
 I-3 R^4 , R^5 and R^6 are each hydrogen or C_1 - C_3 -alkyl,
 I-3 E is oxygen or methylene,
 I-3 X is oxygen or sulfur,
 I-3 Q is oxygen, sulfur or N⁸,
 I-3 Y is oxygen, sulfur or CHR^4 ,
 I-3 n is 0 or 1,
 I-3 Z is methylene, methyleneoxymethylene, methylenethiomethylene or ethenylene, R^7 is hydrogen, C_1 - C_6 -alkyl, C_1 - C_6 -alkoxyalkyl, C_1 - C_6 -alkylthioalkyl or C_5 - or C_6 -cycloalkyl,
 I-4 R^8 is C_1 - C_8 -alkyl, C_3 - or C_4 -alkenyl, C_3 - or C_4 -alkynyl or C_1 - C_6 -alkoxyalkyl,
 I-4 R^9 is hydrogen, chlorine, bromine, cyano, C_1 - C_4 -alkyl, C_3 - or C_4 -alkenyl, C_3 - or C_4 -alkynyl, C_1 - C_6 -alkoxyalkyl, C_1 - C_6 -alkylthioalkyl or cyclohexylmethyl,
 I-4 R^{10} is hydrogen, halogen, cyano, C_1 - C_4 -alkyl, C_1 - C_3 -alkoxycarbonyl or C_1 - C_4 -alkoxycarbonyl, or R^9 and

R^{10} together form a C_4 - or C_5 -alkylene or C_4 - or C_5 -oxoalkylene group,
 R^{11} is C_1 - C_6 -alkyl, C_3 - or C_4 -alkenyl, C_3 - or C_4 -alkynyl or a group

or $-\text{CH}_2\text{C}(\text{CH}_3)_2\text{COOR}^2$,
 R^{12} is hydrogen or cyano,
 R^{13} is hydrogen or C_1 - C_4 -alkoxycarbonyl,
 R^{14} is C_1 - C_4 -alkyl, C_3 - or C_4 -alkenyl, C_3 - or C_4 -alkynyl, C_1 - C_4 -alkylcarbonyl, C_1 - C_4 -alkoxycarbonyl- C_1 - C_4 -alkyl, tetrahydrofurfuryl, dihydropyranylmethyl, dihydrothiopyranylmethyl, tetrahydropyranylmethyl or tetrahydrothiopyranylmethyl,
 R^{15} is hydrogen, C_1 - C_4 -alkyl, C_3 - or C_4 -alkynyl, C_1 - C_4 -alkoxycarbonyl- C_1 - C_4 -alkyl or $-\text{N}=\text{C}(\text{CH}_3)_2$ and
 R^{16} is hydrogen; C_1 - C_4 -alkyl, C_3 - or C_4 -alkenyl, C_3 - or C_4 -alkynyl, unsubstituted benzyl or benzyl which is, monosubstituted to trisubstituted by halogen or C_1 - C_4 -alkyl, tetrahydrofurfuryl, dihydropyranylmethyl, dihydrothiopyranylmethyl, tetrahydropyranylmethyl or tetrahydrothiopyranylmethyl,
for the desiccation and abscission of plant organs.

The present invention furthermore relates to a method for the desiccation and abscission of plant organs, in particular of the leaves, by means of the above-mentioned compounds I and II.

EP-A 207 894 discloses that specially substituted N-phenyl-3,4,5,6-tetrahydrophthalimides have selected herbicidal properties as well as a plant growth-regulating action. An example indicates the desiccant and defoliant action in cotton plants without specifying the active ingredients. The application rates are 0.6 and 1.2 kg/ha. Evidently no good results were obtained with 0.3 kg/ha.

The use of tetrahydrophthalimide derivatives as herbicides is described in a number of publications, for example in DE-A-36 03 789, DE-A-36 07 300, DE-A-30 13 162, DE-A-31 09 035, DE-A-35 33 440, EP-A-61 741, EP-A-83 055, EP-A-68 822, EP-A-236 916, GB-A-20 71 100, U.S. Pat. No. 3,878,224, JP 59/155 358 and JP 61/027 962. These publications do not disclose the use of the compounds as abscission agents for the controlled induction of the dropping of leaves, blossoms of fruit in crops, such as cotton, citrus fruit, olives, pomes and drupes, and their use as desiccants for drying out the visible parts in crops, for example potato, rape, sunflower and soybean.

There is considerable economic interest in both abscission agents and desiccants, for facilitating harvesting. Particularly in intensive cotton cultivation, the use of defoliants is essential for effective use of picking machines or harvesting the bolls. The commercial products used to date do not meet essential requirements in practice, for example rapid and lasting activity even under cooled temperature conditions, low application rates and no environmental pollution (toxicity, odor and flammability).

We have found that the N-phenyl-3,4,5,6-tetrahydrophthalimides defined at the outset have high activity with regard to the abscission and desiccation of plant organs. Their use has considerable advantages compared with known agents:

a) Their action is optimum even at low application rates of about 60-250 g/ha,

b) Their effect is much more complete at a comparable application rate and
c) Their action is much more reliable even at low temperatures.
5 In addition to their excellent action as defoliants, the compounds I and/or II have very good activity when they are used as desiccants for drying out the visible parts of crop plants, for example potatoes, sunflower, soybean and rape, in order to facilitate the harvesting process. Furthermore, they 10 result in uniform ripening of the fruit to be harvested.

The compounds which are particularly preferred because of their activity are N-phenyl-3,4,5,6-tetrahydrophthalimides of the structure I, where R is fluorine or, in particular, hydrogen.

Preferred radicals A are the following groups:

where [Q is oxygen,] R^1 is H, Cl, Br, CN or C_1 - C_6 -alkyl, in particular C_1 - C_4 -alkyl, and R^2 is H, C_1 - C_8 -alkyl, in particular C_1 - C_4 -alkyl, such as methyl, ethyl, propyl, isopropyl, n-butyl or isobutyl, $[C_1$ - C_8 -alkenyl] C_2 - C_8 -alkenyl, in particular $[C_1$ - C_4 -alkenyl], C_2 - C_4 -alkenyl, C_3 - or $[C_4$ -alkynyl] C_4 -alkynyl, $[C_1$ - C_8 - C_4 -alkylthio- C_1 - C_4 -alkyl], C_1 - C_4 -alkylthio- C_1 - C_4 -alkyl, C_1 - C_{17} -aralkyl, for example phenylalkyl, such as benzyl or 2-phenylethyl, or C_3 - C_6 -cycloalkyl, in particular C_5 - or C_6 -cycloalkyl, such as cyclopentyl or cyclohexyl,

where X is O or S, n is 0 or 1, R^3 is H or C_1 - C_4 -alkyl as stated for R_2 , which may be substituted by hydroxyl, halogen, such as fluorine, chlorine or bromine, cyano, mercapto, C_1 - C_4 -alkoxy, C_1 - C_4 -alkylthio, C_1 - C_4 -alkylcarbonyloxy or C_1 - C_4 -alkoxycarbonyl- C_1 - C_4 -alkylthio, and R^4 is hydrogen or C_1 - C_3 -alkyl,

OR¹⁴

I-2

where R^{14} is, in particular, tetrahydrofurfuryl, dihydropyranylmethyl, dihydrothiopyranylmethyl, tetrahydropyranylmethyl or tetrahydrothiopyranylmethyl.

The N-substituted tetrahydrophthalimides I are obtainable 55 from 3,4,5,6-tetrahydrophthalic anhydride and appropriately substituted aniline derivatives, which can be prepared by reduction of the corresponding nitro compounds. As a rule, the reaction is carried out in an inert solvent at from 20° to 200° C., preferably from 40° to 50° C. Examples of suitable 60 solvents are lower alkanecarboxylic acids, such as glacial acetic acid or propionic acid, or aprotic solvents, such as toluene or xylene, in the presence of acidic catalysts, for example aromatic sulfonic acids.

Cyanoalkyl-substituted N-phenyltetrahydrophthalimides 65 are described in EP-A 68 822.

N-phenyltetrahydrophthalimides in which A is a group I-1 are disclosed in DE-A 36 03 789 (EP-A 240 659) or DE-A

37 24 399 (EP-A-300 387). They can also be prepared by reacting an aldehyde of the formula IV

with a phosphorane of the formula V

where Ar is unsubstituted or substituted phenyl at from -10° to 100° C. and in the presence of a solvent. The aldehydes of the general formula IV which are used as starting materials are obtainable in a simple manner by the methods described in German Patent Application 3815042.5 (O.Z. 0050/39993). The radical R of these compounds may be hydrogen or fluorine.

The phosphoranes V which are required for the preparation of the tetrahydrophthalimides and which are also referred to as phosphorylides are obtainable by methods known from the literature (for example Houben-Weyl, Methoden der Organischen Chemie, Vol. E1, pages 636–639, Georg-Thieme Verlag, Stuttgart 1982).

The reaction of the starting compounds IV and V is in general advantageously carried out in the presence of a solvent. Suitable solvents are all solvents conventionally used for carrying out Wittig reactions, for example halogenated solvents, such as chloroform, or ethers, such as tetrahydrofuran, dioxane or ethylene glycol dimethyl ether. Preferred solvents are alcohols, in particular C₁-C₄-alcohols, such as methanol, ethanol, propanol, isopropanol, butanol, isobutanol or tertbutanol. The solvents can also be used in the form of solvent mixtures but as a rule the pure solvents are preferably employed. If alcohols are used as solvents, it is generally advantageous to use as a solvent that alcohol which corresponds to the alcohol component of the ester group in I and V.

Of course, the optimum reaction temperature depends on the particular starting compounds IV and V to be reacted and on the solvent used. In general, however, the reaction is carried out at from -10° to 100° C., preferably from -10° to 60° C., particularly advantageously from 10° to 40° C.

The starting compounds IV and V can be reacted with one another in stoichiometric amounts. However, it may prove advantageous if one of the two reactants, IV or V, is used in the reaction in a molar excess of from 10 to 20%.

N-phenyltetrahydronaphthalimides in which the Group A is I-2 or I-3 are described in German Applications P 37 41 272.8 and P 37 41 273.6. Compounds in which A is I-4 or I-5 are disclosed in DE-A-36 03 789 (EP-A-240 659). N-phenyltetrahydronaphthalimides in which A is I-6 and I-7 are described in German Applications P 37 41 272.8 and P 38 19 464.3. Compounds I in which A is I-8 and I-9 are disclosed in DE-A-37 24 395 (EP-A-300 398) and 36 07 300 (EP-A-236 916). Compounds I in which A is I-10 are described in German Application P 37 36 297.6. Compounds I in which A is I-11 are disclosed in DE-A-31 09 035 and 35 33 440 and in GB-A-20 71 100.

N-aryltetrahydrophthalimide compounds of the structure II can be obtained by reacting a correspondingly substituted amine III

with an N-alkylating compound Z-R¹⁶, where Z is an acid radical which initiates N-alkylation, and reacting the resulting amine in a conventional manner with tetrahydrophthalic anhydride. It is also possible first to carry out the reaction of III with tetrahydrophthalic anhydride and then to effect N-alkylation. Preferred alkylating agents are halogen compounds, tosylates or mesylates of the radicals to be introduced. The preparation of compounds of the structure II is described in, for example, German Application P 38 07 295 5.

23.3.1. The active ingredients I and/or II may be used, for example, in the form of directly sprayable solutions, 25 powders, suspensions, including concentrated aqueous, oily or other suspensions or dispersions, emulsions, oil dispersions, pastes, dusting agents, broadcasting agents or granules, by spraying, atomizing, dusting, broadcasting or pouring. The application forms depend entirely on the 30 intended uses; they should in any case ensure very fine distribution of the novel active ingredients.

Mineral oil fractions having a medium to high boiling point, such as kerosine or diesel oil, and coal tar oils and vegetable or animal oils, aliphatic, cyclic and aromatic hydrocarbons, e.g. benzene, toluene, xylene, paraffin, tetrahydronaphthalene, alkylated naphthalenes or their derivatives, for example methanol, ethanol, propanol, butanol, chloroform, carbon tetrachloride, cyclohexanol, cyclohexanone, chlorobenzene, isophorone, highly polar solvents, e.g. dimethylformamide, dimethylsulfoxide, N-methylpyrrolidone or water, are suitable for the preparation of directly sprayable solutions, emulsions, pastes or oil dispersions.

Aqueous application forms can be prepared from emulsion concentrates, pastes or wettable powders (spray powders, oil dispersions) by adding water. To prepare emulsions, pastes or oil dispersions, the substances as such may be dissolved in an oil or solvent and homogenized in water by means of wetting agents, adhesives, dispersants or emulsifiers. However, it is also possible to prepare concentrates which consist of active substance, wetting agents, adhesives, dispersants or emulsifiers and possibly solvents or oil and which are suitable for dilution with water.

polyether alcohols, isotridecyl alcohol, fatty alcohol ethylene oxide condensates, ethoxylated castor oil, polyoxyethylene alkyl ethers, ethoxylated polyoxypropylene, lauryl alcohol polyglycol ether acetal, sorbitol esters, ligninsulfite waste liquors and methylcellulose.

Powder, broadcasting, coated, impregnated and homogeneous granules can be prepared by binding the active ingredients to solid carriers. Solid carriers are mineral earths, such as silica gel, silicas, silicates talc, kaolin, atta clay, limestone, lime, chalk, bole, loess, clay, dolomite, kieselguhr, calcium sulfate, magnesium sulfate, magnesium oxide, milled plastics, fertilizers, e.g. ammonium sulfate, ammonium phosphate, ammonium nitrate, ureas and vegetable products, such as cereal meal, ground bark, woodmeal, nutshell meal and cellulose powder, and other solid carriers.

The formulations contain from 0.1 to 95, preferably from 0.5 to 90% by weight of active ingredient.

Examples of formulations are:

I. 90 parts by weight of the compound according to Example 1.1 are mixed with 10 parts by weight of N-methyl- α -pyrrolidone to give a solution which is suitable for use in the form of very small drops.

II. 20 parts by weight of the compound of Example 1.17 are dissolved in a mixture which consists of 80 parts by weight of xylene, 10 parts by weight of the adduct from 8 to 10 moles of ethylene oxide with 1 mole of oleic acid N-monoethanolamide, 5 parts by weight of the calcium salt of dodecylbenzenesulfonic acid and 5 parts by weight of the adduct of 40 moles of ethylene oxide with 1 mole of castor oil. By pouring the solution into 100,000 parts by weight of water and finely dispersing it, an aqueous dispersion which contains 0.02% by weight of the active ingredient is obtained.

III. 20 parts by weight of compound No. 1.17 are dissolved in a mixture which consists of 40 parts by weight of cyclohexanone, 30 parts by weight of isobutanol, 20 parts by weight of the adduct of 7 moles of ethylene oxide with 1 mole of isoctylphenol and 10 parts by weight of the adduct of 40 moles of ethylene oxide and 1 mole of castor oil. By pouring the solution into 100,000 parts by weight of water and finely dispersing it, an aqueous dispersion which contains 0.02% by weight of the active ingredient is obtained.

IV. 20 parts by weight of compound No. 4.1 are dissolved in a mixture which consists of 25 parts by weight of cyclohexanol, 65 parts by weight of a mineral oil fraction boiling within a range from 210° to 280° C. and 10 parts by weight of the adduct of 40 moles of ethylene oxide with 1 mole of castor oil. By pouring the solution into 100,000 parts by weight of water and finely dispersing it, an aqueous dispersion which contains 0.02% by weight of the active ingredient is obtained.

V. 20 parts by weight of compound No. 1.26 are mixed thoroughly with 3 parts by weight of the sodium salt of diisobutylnaphthalene- α -sulfonic acid, 17 parts by weight of the sodium salt of a ligninsulfonic acid from a sulfite waste liquor and 60 parts by weight of silica gel powder, and the mixture is milled in a hammer mill. By finely distributing the mixture in 20,000 parts by weight of water, a spray liquor which contains 0.1% by weight of the active ingredient is obtained.

VI. 30 parts by weight of compound No. 1.26 are mixed with 97 parts by weight of finely divided kaolin. A dusting agent which contains 3% by weight of the active ingredient is obtained in this manner.

VII. 30 parts by weight of compound No. 1.17 are thoroughly mixed with a mixture of 92 parts by weight of

silica gel powder and 8 parts by weight of paraffin oil, which has been sprayed on the surface of this silica gel. A formulation of the active ingredient having good adhesion is obtained in this manner.

VIII. 20 parts by weight of compound No. 1.17 are mixed thoroughly with 2 parts of the calcium salt of dodecylbenzenesulfonic acid, 8 parts of a fatty alcohol polyglycol ether, 2 parts of the sodium salt of a phenolsulfonic acid/urea/formaldehyde condensate and 68 parts of a paraffinic mineral oil. A stable oily dispersion is obtained.

The action and the rate of action can be promoted, for example, by means of additives which increase the action, such as organic solvents, wetting agents and oils. This allows the application rate of the actual active ingredient to be reduced.

The application rate of the individual active ingredients is varied according to the desired effect, plant species, stage of development of the plants to be treated and agents to be used.

The agents are supplied to the plants mainly by spraying the foliage. Application may be effected, for example using water as a carrier, by conventional spraying techniques using amounts of spray liquor of about 100–1,000 l/ha. The agents can be applied both by the low volume and ultra low volume methods and in the form of microgranules.

The novel agents can be used in application rates of from 0.001 to 5, preferably from 0.01 to 3, in particular from 0.01 to 0.6, kg/ha.

The agents can be applied either alone or as a mixture with other agents or with other active ingredients. If necessary, other defoliants, desiccants, crop protection agents or pesticides can be added, depending on the desired purpose.

It has also been found that mixtures of the novel agents with, for example, active ingredients (A)–(C) stated below lead to further promotion of the desiccant and defoliant effect and help to achieve better control of the undesirable resprouting of plants after desiccation or defoliation (particularly in cotton):

- (A) Herbicidal active ingredients from the group consisting of
  - a. chloroacetanilides, for example 2-chloro-N-(2,6-dimethylphenyl)-N-(1H-pyrazol-1-ylmethyl)-acetamide (common name: metazachlor) described in German Laid-Open Application DOS 2,648,008,
  - b. substituted quinoline-8-carboxylic acids, for example 3,7-dichloroquinoline-8-carboxylic acid (common name: quinchlorac) described in EP-A-60 429 and 3-methyl-7-chloroquinoline-8-carboxylic acid (common name: quinmerac) described in EP-A-104 389,
  - c. cyclohexenone derivatives, for example 2-(1-ethoxyimino)-butyl]-5-[2-(ethylthio)-propyl]-3-hydroxy-2-cyclohexenone (common name: sethoxydim) described in German Laid-Open Application DOS 2,822,304 and 2-[1-(ethoxyimino)-butyl]-3-hydroxy-5-(2H-tetrahydrothiopyran-3-yl)-2-cyclohexen-1-one (common name: cycloxydim) described in German Laid-Open Application DOS 3,121,355,
  - d. phenoxyalkanecarboxylic acids, for example (4-chloro-2-methylphenoxy)-acetic acid,
  - e. 3-(isopropyl)-1H-2,1,3-benzothiadiazin-4-(3H)-one 2,2-dioxide, described in German Laid-Open Application DOS 1,542,836 (Bentazon®),
  - f. dinitroanilines, for example N-(1-ethylpropyl)-3,4-dimethyl-2,6-dinitroaniline described in German Laid-Open Application DOS 2,241,408,
  - g. imidazolinones, for example 2-[4,5-dihydro-4-methyl-4-(1-methylethyl)-5-oxo-1H-imidazol-2-yl]-3-

quinolinecarboxylic acid (Scepter®, common name: imazaquin); 2-(4-isopropyl-4-methyl-5-oxo-2-imidazolin-2-yl)-nicotinic acid combined with isopropylamine in a ratio of 1:1 (Arsenal®, common name: imazapyr); 2-[4,5-dihydro-4-methyl-4-(1-methylethyl)-5-oxo-1H-imidazol-2-yl]-5-ethyl-3-pyridinecarboxylic acid (Pursuit®, common name: imazethapyr); methyl 2-(4-isopropyl-4-methyl-5-oxo-2-imidazolin-2-yl)-*p*-toluate combined with methyl 6-(4-isopropyl-4-methyl-5-oxo-2-imidazolin-2-yl)-*m*-toluate (Assert®, common name: imazamethabenz) and imazamethapyr (common name; trade mark: Cadre®), and

h. sulfonylurea derivatives, for example the compounds listed in Tables i and ii below and 1-(4,6-dimethoxypyrimidin-2-yl)-3-(ethylsulfonyl)-2-pyridylsulfonyl)-urea, known as DPX-E 9636.

Hetarylsulfonylureas| A'	R³'	R⁴'	Z'	disclosed in
	COOCH ₃	OCH ₃	OCH ₃	CH

The commercial products listed in Tables i and ii are known, for example, under the trade names Glean®, Ally®, Express®, Logran®, Setoff®, Muster®, Londax®, Oust®, Classic®, Beacon®, Harmony® or Remedy®.

i. Diphenyl ether derivatives, such as 5-[2-chloro-4-(trifluoromethyl)-phenoxy]-2-nitrobenzoic acid described in DE-A-23 11 638 and EP-A-40 898 and its salts (acifluorfen) and ethoxycarbonylmethyl 5-[2-chloro-4-(trifluoromethyl)-phenoxy]-2-nitrobenzoate (fluoroglycofen) and the diphenyl ether 1-(carboethoxy)-ethyl 5-[2-chloro-4-(trifluoromethyl)phenoxy]-2-nitrobenzoate (common name: lactofen, Cobra®, 2-chloro-1-(3-ethoxy-4-nitrophenoxy)-4-trifluoromethylbenzene (common name: oxyfluorfen) and 5-(2-chloro-4-trifluoromethyl)-phenoxy)-N-methylsulfonyl)-2-nitrobenzamide (common name: fomesafen, Flex®, EP-A-3416).

(B) Defoliants and desiccants as mentioned, for example, in G. W. Cathey (1986), Physiology of defoliation in cotton production, in Cotton Physiology (J. R. Mauney, J. McD. Stewart, eds.) The Cotton Foundation reference book series, No. 1, Chapter 14, 143-153, in Morgan, P. W. (1985)

45 Chemical manipulation of abscission and desiccation. In Agricultural Chemicals of the Future (J. L. Hilton, ed.) BARC Symposium 8, 61-74. Rowman & Allanheld, Totowa, in R. Krämer (1989) Erstellung leistungsfähiger Kernobstjungpflanzen, thesis at the Faculty of Agriculture of 50 the University of Bonn, and in H. Bergmann, D. Martin (1989), Chemical manipulation of desiccation and defoliation and essential aspects for the application and development of new chemical compounds in the future, in Chemistry of Plant Protection 2 (G. Haug, H. Hoffmann, eds.) 55 197-246, Springer-Verlag Berlin, Heidelberg.

a. Urea derivatives, for example N-phenyl-N'-1,2,3-thiadiazol-5-ylurea disclosed in German Laid-Open Application DOS 2,506,690, N-phenyl-N'-1,3,4-thiadiazol-2-ylurea described in German Laid-Open Application DOS 3,612,830 or N-phenyl-N'-2-chloropyrid-3-ylurea described in German Laid-Open Application DOS 2,843,722 or the above-mentioned 3-(3-chloro-4-methoxyphenyl)-1,1-dimethylurea (common name: metoxuron),

60 b. (2-chloroethyl)-phosphonic acid (Ethrel®),
c. S,S,S-tributyl phosphorotri thioate and S,S,S-tributyl phosphorotri thioite,

11

- d. 2,3-dihydro-5,6-dimethyl-1,4-dithiin 1,1,4,4tetraoxide (Harvade®),
  - e. salts of N-(phosphonomethyl)-glycine, such as the isopropylammonium salt (Roundup®),
  - f. ammonium DL-homoalanin-4-yl-(methyl)-phosphinate (ammonium glufosinate),
  - 5 g. magnesium chloride and sodium chloride,
  - h. ammonium sulfate and nitrate,
  - i. hydrogen cyanamide, calcium cyanamide,
  - j. potassium iodide,
  - k. Cu ethylenediaminetetraacetate and Fe ethylenediaminetetraacetate,
  - 10 l. arsenic acid and its derivatives, such as hydroxydimethylarsine oxide (common name: dimethylarsenic acid),
  - m. 1,2-dihydropyridazine-3,6-dione,
  - n. 7-oxabicyclo[2.2.1]heptane-2,3-dicarboxylic acid 15 (common name: endothall),
  - o. 6,7-dihydrodipyridol (1,2- α :2',1'-c)pyridinium ion as dibromide monohydrate salt (common name: diquat) and 1,1'-dimethyl-4,4'-bipyridinium ion as dichloride or dimethylsulfate salt (common name: paraquat),
  - 20 p. 3,5-dibromo- or diiodo-4-hydroxybenzonitrile (common name: bromoxynil),
  - q. substituted dinitrophenols, such as 2-sec-butyl-4,6-dinitrophenol (common name: dinoseb),
  - r. triazine derivatives, such as 2-ethylamino-4- 25 isopropylamino-6-methylthio-1,3,5-triazine (common name: ametryne),
  - s. triazole derivatives, such as 1H-1,2,4-triazol-3-ylamine (common name: amitrol),
  - t. benzothiazoles, such as 2-n-butylmercaptobenzothiazole 30 (common name: butylcaptax), and
  - u. di-n-butyl 1-n-butylaminocyclohexyl phosphonate (common name: buminafos).
- (C) Growth retardants from the group consisting of
- a. quaternary ammonium salts from the group consisting of 35 the
    - N,N-dimethylazacycloheptanium salts, N,N-dimethylpiperidinium salts,
    - N,N-dimethylhexahydropyridazinium salts, N,N-dimethyltetrahydropyridazinium salts,
    - 40 N-methylpyridinium salts,
    - N,N-dimethylpyrrolidinium salts
    - and N,N,N-trimethyl-N-2-chloroethylammonium salts, in particular N-2-chloroethyl-N-trimethylammonium 45 chloride (common name: chlormequat chloride) and N,N-dimethylpiperidinium chloride (common name: mepiquat chloride),
  - b. pyrimidine compounds, such as those disclosed in U.S. Pat. No. 3,818,009 and in Journal of Plant Growth Regulation 7 : 27, 1988 (for example those having the common name: ancymidol or flurprimidol),
  - c. pyridine compounds disclosed in DE-A-30 15 025,
  - d. norbornadiazetines, as described in German Laid-Open 55 Applications DOS 2,615,878 and DOS 2,742,034,
  - e. growth-regulating triazole compounds as described in European Application 88104320.2, in British Crop Protection Conference - Weeds 1982, Vol. 1, BCPC Publications, Croydon 1982, page 3, in Plant Cell Physiol., 611, in Pestic. Sci. 19, 153, in J. Agron. Crop Sci. 158, 324 or in J. Plant Growth Regul. 4, 181, for example 1-phenoxy-3-(1H-1,2,4-triazol-1-yl)-4-hydroxy-5,5-dimethylhexane,
  - 60 f. 2-acyl-3-hydroxycyclohex-2-en-1-ones, as described in, for example, EP-A-126 713 or 123 001,

12

- g. 1-(4-chlorophenoxy)-3,3-dimethyl-1-[1,2,4-triazol-1-yl]-butan-2-one (common name: triadimefon), N-[2,4-dimethyl-5-[trifluoromethylsulfonyl]amino]-phenylacetamide (common name: mefluidide), 2-chloro-2',6'-diethyl-N-[methoxymethyl]-acetanilide (common name: alachlor), S-ethyl dipropylthiocarbamate (common name: EPTC) and succinic acid 2,2-dimethylhydrazide (common name: daminozid).
- For example, the following mixing partners can be added:
- 2-Methyl-6-ethylethoxymethyl-2-chloroacetanilide
- 2-Methyl-6-N-(methoxy-1-methylethyl)-2-chloroacetanilide
- 2-6-Dimethyl-N-(1H-pyrazol-1-ylmethyl)-2-chloroacetanilide
- 2,6-Diethyl-N-(methoxymethyl)-2-chloroacetanilide
- 3-Methyl-7-chloroquinoline-8-carboxylic acid (salts, esters)
- 3,7-Dichloroquinoline-8-carboxylic acid (salts, esters)
- 2-[(1-Ethoxymino)-butyl]-5-[2-(ethylthio)-propyl]-3-hydroxy-2-cyclohexan-1-one (salts)
- 2-[(1-Trans-chloroallyloxyimino)-butyl]-5-[2-(ethylthio)-propyl]-3-hydroxy-2-cyclohexan-1-one (salts)
- 2-[(1-Trans-chloroallyloximino)-propyl]-5-[2-(ethylthio)-propyl]-3-hydroxy-2-cyclohexan-1-one (salts)
- 2-[(1-Ethoximino)-butyl]-5-[2-H-tetrahydrothiopyran-3-yl]-3-hydroxy-2-cyclohexan-1-one (salts)
- 2-[(1-Ethoximino)-propyl]-5-(2,4,6-trimethylphenyl)-3-hydroxy-2-cyclohexan-1-one (salts)
- 2-Methyl-4-chlorophenoxyacetic acid (salts, esters, amides)
- 2-[2-Methyl-4-chlorophenoxy]-propionic acid (salts, esters, amides)
- 4-[2-Methyl-4-chlorophenoxy]-butyric acid (salts, esters, amides)
- 4-[2,4-Dichlorophenoxy]-butyric acid (salts, esters, amides)
- 2,4-Dichlorophenoxyacetic acid (salts, esters, amides)
- 3,5,6-Trichloropyridyl-2-oxyacetic acid (salts, esters, amides)
- 3-(1-Methylethyl)-1-H-2,1,3-benzothiadiazin-4(3H)-one-2,2-dioxide (salts)
- 3-(1-Methylethyl)-1-cyano-2,1,3-benzothiadiazin-4-(3H)-one-2,2-dioxide (salts)
- N-(1-Ethylpropyl)-3,4-dimethyl-2,6-dinitroaniline
- 2-[4,5-Dihydro-4-methyl-4-(1-methylethyl)-5-oxo-1H-imidazol-2-yl]-3-quinolinecarboxylic acid
- 2-(4-Isopropyl-4-methyl-5-oxo-2-imidazolin-2-yl)-nicotinic acid (salts, esters)
- Methyl-3-[[[(4-methoxy-6-methyl-1,3,5-triazin-2-yl)amino]-carbonyl]-amino]-sulfonyl]-2-thiophenecarboxylate (Harmony®)
- 1-(4,6-Dimethoxypyrimidin-2-yl)-3-(ethylsulfonyl)-2-(pyridylsulfonyl)-urea
- 2-[2,4-Dichlorophenoxy]-proionic acid (salts, esters, amides)
- 5-[2-Chloro-4-(trifluoromethyl)-phenoxy]-2-nitrobenzoic acid (salts)
- N-phenyl-N'-1,2,3-thiadiazol-5-ylurea
- N-phenyl-N'-1,3,4-thiadiazol-2-ylurea

13

N-phenyl-N'-2-chloropyrid-3-ylurea
 N-3,4-(Dichlorophenyl)-N',N'-dimethylurea
 3-(3-Chloro-4-methoxyphenyl)-1,1-dimethylurea
 2-Chloroethylphosphonic acid
 5 S,S,S-Tributyl phosphorotrihioate
 S,S,S-Tributyl phosphorotrihioite
 10 2,3-Dihydro-5,6-dimethyl-1,4-dithiin-1,1,4,4-tetraoxide
 N-(Phosphonomethyl)-glycines (salts)
 Ammonium-DL-homoalanin-4-ylmethylphosphinate
 Magnesium chloride and sodium chloride
 Ammonium sulfate and nitrate
 Cyanamides
 Potassium iodide
 15 Copper chelates and iron chelates,
 Arsenic acid
 Hydroxydimethylarsine oxide
 20 1,2-Dihydropyridazine-3,6-dione
 7-Oxabicyclo[2.2.1]heptane-2,3-dicarboxylic acid (salts,
 esters, amides)
 6,7-Dihydropyridol (1,2- α :2',1'-c)pyridilium ion as the
 25 dibromide monohydrate salt
 1,1'-Dimethyl-4,4'-dipyridinium ion as the dichloride or
 dimethylsulfate salt
 3,5-Dibromo-4-hydroxybenzonitrile
 3,5-Diiodo-4-hydroxybenzonitrile
 2-Sec-butyl-4,6-dinitrophenol
 2-Tert-butyl-4,6-dinitrophenol
 2-Sec-amyl-4,6-dinitrophenol
 2-Ethylamino-4-isopropylamino-6-methylthio-1,3,5-
 30 triazine
 1H-1,2,4-Triazol-3-ylamine
 2-n-Butylmercaptobenzothiazole
 Di-n-butyl-1-n-butylaminocyclohexyl phosphonate
 N,N,N-Trimethyl-N-2-chloroethylammonium salts
 N,N-Dimethylpiperidinium salts
 N-Methylpyridinium salts
 α -Cyclopropyl- α -(4-methoxyphenyl)-5-

 trifluoromethylphenyl)-propen-2-ol
 30 Particularly preferred N-phenyl-3,4,5,6-tetrahydrophthalimides are those of the formula I where R is
 a low molecular weight alkyl radical and A is the group I-1
 in which Q is oxygen, R¹ is chlorine or bromine and R² is
 C₁-C₆-alkyl. The compounds No. 1.1 and in particular No.
 35 1.17 are noteworthy here.
 Preferred application rates for these compounds are from
 0.02 to 1.0, in particular from 0.05 to 0.5, kg/ha.
 Preferred partners for the mixture are listed in the Table
 40 below, where the relevant application rates of the partner of
 the mixture are also stated. The total application rate for the
 mixture can be determined from the sum of the amount
 stated for the tetrahydrophthalimides I and the amount stated
 in each case in the Table.

TABLE

Partner in the mixture	Application rate kg/ha
3,7-Dichloroquinoline-8-carboxylic acid (salts, esters) (quinclorac)	0.05-0.5
2,4-Dichlorophenoxyacetic acid (salts, esters, amides)	0.05-1
2-[4,5-Dihydro-4-methyl-4-(1-methylethyl)-5-oxo-1H-imidazol-2-yl]-3- quinoliniccarboxylic acid (imazaquin)	0.005-0.25
Methyl 3-[[[(4-Methoxy-6-methyl-1,3,5-triazin-2-yl)-amino]-carbonyl]- amino]-sulfonyl]-2-thiophenecarboxylate (Harmony ®)	0.001-0.1
1-(4,6-Dimethoxypyrimidin-2-yl)-3-(ethylsulfonyl)-2-pyridylsulfonyl)-urea (DPX-E 9636)	0.001-0.1
5-[2-Chloro-4-(trifluoromethyl)-phenoxy]-2-nitrobenzoic acid (salts) (acifluorfen)	0.1-1
N-Phenyl-N'-1,2,3-thiadiazol-5-ylurac (thidrazuron)	0.01-0.5
(2-Chloroethyl)-phosphonic acid (ethephon)	0.2-4
S,S,S-Tributyl phosphorotrihioate (def)	0.2-2
S,S,S-Tributyl phosphorotrihioite (folex)	0.2-2
Sodium chloride	0.4-4
7-Oxabicyclo[2.2.1]heptane-2,3-dicarboxylic acid (endothall)	0.2-2
1,1'-Dimethyl-4,4'-bipyridinium ion as the dichloride or dimethylsulfate salt (paraquat)	0.01-1
N,N-Dimethylpiperidinium chloride (mepiquat chloride)	0.05-2
6,7-Dihydropyridol(1,2- α :2',1'-c)pyridilium dibromide (diquat)	0.1-1
2-Sec-Butyl-4,6-dinitrophenol (dinoseb)	0.5-5

The Examples which follow describe methods for the preparation of compounds I and II which have been disclosed in earlier applications not yet laid open. The active ingredients stated in the Tables can be obtained by appropriate modification of the starting materials.

PREPARATION EXAMPLES

A) Compounds I in which A=I-2 or I-3

a) 9.9 g of ethane 1,2-dithiol are added to 18.6 g of 2-chloro-5-nitrobenzaldehyde and 0.5 g of p-toluenesulfonic acid in 250 ml of toluene and the mixture is refluxed for 5 hours under a water separator. After the mixture has been cooled, the solvent is removed, the residue is stirred with petroleum ether and the product is filtered off and dried. 25.5 g of 4-chloro-3-(1,3-dithiolan-2-yl)-nitrobenzene (mp. 130–131° C.) are obtained.

b) 24.9 g of the above nitro compound are added a little at a time to a refluxing mixture of 15.9 g of iron powder in 50 ml of methanol and 75 ml of glacial acetic acid, and the mixture is refluxed for 2 hours. After the mixture has been cooled, 250 ml of water are added and the solid is filtered off. The filtrate is extracted with 3 times 100 ml of ethyl acetate, the extracts are dried and evaporated down and the residue is precipitated from petroleum ether, filtered off under suction and dried. 21.5 g of 4-chloro-3-(1,3-dithiolan-2-yl)-aniline (mp. 60–63° C.) are obtained.

c) 11.6 g of the above aniline and 7.6 g of cyclohexene-1,2-dicarboxylic anhydride in 150 ml of glacial acetic acid are stirred for 2 days at room temperature, and the precipitate which separates out is filtered off, washed with water and petroleum ether and dried. 13 g of N-[4-chlorophenyl-3-(1,3-dithiolan-2-yl)]-3,4,5,6-tetrahydronphthalimide (mp. 155–158° C.) are obtained.

Further examples of active ingredients which can be prepared using this principle of synthesis are shown in Tables 2 and 3.

B) Compounds in which A=I-6

N-[4-chloro-3-(4'-methyl-2'-oxo-3'-oxacyclopentylidenemethyl)-phenyl]-3,4,5,6-tetrahydronphthalimide

a) 7.1 g (0.03 mole) of 4-methyl-2-oxo-3-oxacyclopentyl diethylphosphonate [Z. Naturforsch B. 38B (4), 493 (1983)] in 8 ml of absolute tetrahydrofuran are added to a mixture of 7.4 g (0.054 mole) of potassium carbonate and 3.5 g (0.0135 mole) of 18-crown-6 in 10 ml of absolute tetrahydrofuran at

0–5° C., while stirring. After about 0.5 h, 5.0 g (0.027 mole) of 2-chloro-5-nitrobenzaldehyde in 6 ml of absolute tetrahydrofuran are added and stirring is continued for 15 h at room temperature. The mixture is worked up by pouring it onto 40 ml of ice water and extracting it several times with ether. The organic phase is washed with 10% strength HCl and H₂O and dried and the solvent is evaporated off, after which the product is separated over silica gel using 9:1 toluene/acetone as an eluant. 1.7 g of 2-(4'-methyl-2'-oxo-3'-oxacyclopentylidenemethyl)-4-nitrochlorobenzene (mp. 87–103° C., isomer mixture) are obtained in this manner.

b) 2.4 g (0.009 mole) of 2-(4'-methyl-2'-oxo-3'-oxacyclopentylidenemethyl)-4-nitrochlorobenzene in 10 ml of glacial acetic acid and 10 ml of methanol are added to a mixture of 3.0 g (0.054 mole) of iron powder, 7.5 ml of glacial acetic acid and 15 ml of methanol in the course of 15 min at 60° C., while stirring. After the end of the addition, the refluxed mixture is stirred for 30 min, cooled to room temperature and filtered, and the solvent is stripped off under reduced pressure. The residue is taken up in ethyl acetate, the solution is washed and dried and the solvent is removed. 2.3 g of crude 4-amino-2-(4'-methyl-2'-oxo-3'-oxacyclopentylidenemethyl) chlorobenzene, which is reacted without further working up, are obtained in this manner.

c) 2.2 g (0.009 mole) of 4-amino-2-(4'-methyl-2'-oxo-3'-oxacyclopentylidenemethyl) -chlorobenzene, 1.4 g (0.009 mole) of 3,4,5,6-tetrahydronphthalic anhydride and 25 ml of glacial acetic acid are refluxed together for 2 while stirring. The mixture is cooled to room temperature, after which the solvent is stripped off, the residue is taken up in 100 ml of ethyl acetate, the solution is washed and dried and the solvent is removed. This procedure gives 3.5 g of crude product, which, after chromatography over silica gel using 98:2 toluene/acetone, gives 2.5 g of N-[4-chloro-3-(4'-methyl-2'-oxo-3'-oxacyclopentylidenemethyl)-phenyl]-3,4,5,6-tetrahydronphthalimide (mp. 98–113° C.).

Further examples of active ingredients which can be prepared using this principle of synthesis are shown in Table 8.

a) 19.4 g of n-butyl 2,3-dihydroxyisobutyrate are added to 18.6 g of 2-chloro-5-nitrobenzaldehyde and 0.5 g of p-toluenesulfonic acid in 250 ml of toluene, and the mixture is refluxed for 5 hours under a water separator. After the mixture has been cooled, the solvent is removed and the residue is dried under greatly reduced pressure. 35 g of 3-(5-methyl-5-n-butoxycarbonyl-1,3-dioxolan-2-yl)-4-chloronitrobenzene (oil) are obtained.

b) 34.4 g of the above nitro compound in 20 ml of methanol are added to a mixture of 16.8 g of iron powder in 30 ml of methanol and 75 ml of glacial acetic acid, the mixture being refluxed for two hours. After the mixture has been cooled, 250 ml of water are added and the mixture is

17

filtered off under suction. The filtrate is extracted 3 times with 100 ml of ethyl acetate, the extracts are dried and evaporated and the residue is dried under greatly reduced pressure. 31 g of 3-(5-methyl-5-n-butoxycarbonyl-1,3-dioxolan-2-yl)-4-chloroaniline (oil) are obtained.

c) 15.7 g of the above aniline and 7.6 g of cyclohexene-1,2-dicarboxylic anhydride in 150 ml of glacial acetic acid are refluxed for 5 hours. After the mixture has been cooled, 150 ml of water are added, the mixture is extracted with twice 100 ml of methylene chloride and dried and the solvent is removed. The product is purified by chromatography and -dried under greatly reduced pressure. 9.0 g of N-[3-(5-methyl-5-n-butoxycarbonyl-1,3-dioxolan-2-yl)-4-chlorophenyl]-3,4,5,6-tetrahydraphthalimide (oil) are obtained.

Further examples of active ingredients which can be prepared using this principle of synthesis are shown in Table 9.

D) Compounds I in which A=I-8

a) 64.4 g of 2-chlorobenzyl chloride, 76.0 g of ethyl 2-cyanopropionate, 58.0 g of dry potassium carbonate and 0.1 g of 18-crown-6 are refluxed for 3 hours in the absence of moisture. The mixture is filtered off and the residue is distilled to give 69.5 g of ethyl 2-chlorobenzylmethylcyanoacetate (bp.: 107–109° C./0.1)

b) 41.7 ml of concentrated nitric acid (d=1.51) are added to 25.2 g of the ester at from 0° to 5° C. in 30 minutes and the mixture is stirred for a further 30 minutes. The mixture is stirred into 400 ml of ice water and extracted twice with 70 ml of toluene. Washing with 10% strength sodium carbonate solution and water, evaporation of the solvent and recrystallization from 50 ml of diisopropyl ether give 18.9 g of ethyl (2-chloro-5-nitrobenzyl)-methylcyanoacetate (mp.: 714–74° C.).

c) A solution of 18.7 g of nitro compound in 28 ml of methanol and 40 ml of glacial acetic acid is added dropwise to a refluxed mixture of 10.6 g of iron powder in 70 ml of methanol and 15 ml of glacial acetic acid in one hour. The mixture is refluxed for a further 30 minutes and then filtered under suction, and the residue is washed with 50 ml of ethyl acetate. It is stirred into 800 ml of water and extracted with 3 times 100 ml of ethyl acetate. After drying and evaporation of the solvent under reduced pressure, 15.5 g of the ethyl cyanoacetate described above are isolated as a liquid.

This principle of synthesis can be used to prepare, for example, the active ingredients stated in Tables 5 and 6.

18

E) Compounds I in which A=I-10

Variant 1

15 13.9 g of N-(4-chloro-3-hydroxyphenyl)-3,4,5,6-tetrahydraphthalimide, 8.2 g of 3-chloromethyl-5,6-dihydro-2H-thiopyran and 8.3 g of potassium carbonate in 150 ml of acetonitrile are refluxed for hours. The mixture is cooled and filtered, the filtrate is evaporated down, the residue is taken up in 200 ml of methylene chloride and the solution is washed twice with 10% strength sodium hydroxide solution and 3 times with water dried and evaporated out. 15.0 g of N-[4-chloro-3-(3-methoxy-5,6-dihydro-2H-thiopyranyl)-phenyl]-3,4,5,6-tetrahydraphthalimide (mp. 116–119° C.) are obtained.

Variant 2

40 a) 9.6 g of 1-chloro-4-fluoro-5-nitrophenol, 8.2 g of 3-chloromethyl-5,6-dihydro-2H-thiopyran and 3.8 g of potassium carbonate in 150 ml of acetonitrile are relaxed for 5 hours. After cooling and filtration, the filtrate is evaporated down and the residue is taken up in 200 ml of methylene chloride. The organic phase is washed with 3 times 50 ml of water, dried and evaporated down and the residue is stirred with petroleum ether. 12.5 g of 2-chloro-4-fluoro-5-nitro-(5,6-dihydro-2H-thiopyranyl-3-methoxy)-benzene (mp. 91–94° C.) are obtained.

b) 12.2 g of the above nitro compound are added a little at a time to a reflux mixture of 6.7 g of iron powder in 50 ml of methanol and 7.5 ml of glacial acetic acid and refluxing is continued for a further 2 hours. The mixture is cooled, after which 250 ml of water are added and the mixture is filtered off under suction. The filtrate is extracted with 3 times 100 ml of ethyl acetate, the extracts are dried and the solvent is evaporated under reduced pressure. Purification by chromatography gives 5.5 g of 4-chloro-2-fluoro-5-(5,6-dihydro-2H-thiopyranyl-3-methoxy)-aniline (mp. 73–74° C.).

c) 5.5 g of the above aniline and 3.0 g of cyclohexene-1,2-dicarboxylic anhydride in 100 ml of glacial acetic acid are refluxed for 5 hours. The mixture is cooled, after which 50 ml of water are added and filtration is carried out. The precipitate is washed with water and dried. 6.0 g of N-(4-chloro-2-fluoro-5-(5,6-dihydro-2H-thiopyranyl-3-methoxy)-phenyl]-3,4,5,6-tetrahydraphthalimide (mp. 134–137° C.) are obtained.

Further examples of active ingredients which can be prepared using these principles of synthesis are shown in Table 4.

F) Compounds II

a) 4.9 g (0.03 mole) of 6-amino-3,4-dihydro-2H-1,4-benzoxazin-3-one in 50 ml of dimethylformamide are initially taken, 0.79 g (0.033 mole) of sodium hydride is added at 5° C. and the mixture is stirred for 30 minutes at this temperature. Thereafter, 5.9 g (0.033 mole) of 3-bromomethyltetrahydropyran are added, stirring is continued for 3 hours at 60° C., 200 ml of water are added the mixture is extracted twice with 200 ml of methylene chloride, the extracts are dried and the solvent is evaporated under reduced pressure. 5 g (64%) of 4-(tetrahydropyran-4-ylmethyl)-6-amino-3,4-dihydro-2H-1,4-benzoxazin-3-one (oil) are obtained.

b) 4.5 g (0.017 mole) of the above aniline and 2.7 g (0.018 mole) of cyclohexene-1,2-dicarboxylic anhydride in 70 ml of glacial acetic acid are stirred for 3 hours at 70° C. After the mixture has been cooled, 100 ml of water are added, and the precipitate is filtered off, washed with water and dried. 3.5 g (52%) of N-[4-tetrahydropyran-4-ylmethyl]-3,3-dihydro-2H-1,4-benzoxazin-3-on-6-yl]-3,4,5,6-tetrahydropthalimide (mp. 187–189° C.) are obtained.

The active ingredients shown in Tables 10 to 12 can be prepared using this principle of synthesis. Examples of active ingredients of the formulae I and II are shown in Tables 1 to 16 below.

G) Compounds I in which A=I-1 and Q=O

are obtained by a Wittig reaction of

with a phosphorane

10 N-[5-(1'-methoxycarbonyl-1'-bromoethenyl)-4-chloro-2-fluorophenyl]-3,4,5,6-tetrahydropthalimide

4.60 g (15 millimoles) of N-(2-fluoro-4-chloro-5-formylphenyl)-3,4,5,6-tetrahydropthalimide and 6.80 g (16.5 millimoles) of carbomethoxybromomethylenetriphenylphosphorane in 15 ml of methanol are stirred at room temperature for 15 minutes. The reaction mixture is cooled to 0° C. and the precipitated product is filtered off.

Yield: 70%, mp.: 155–157° C.

15 N-[5-(1'-ethoxycarbonyl-1'-chloroethenyl)-4-chloro-2-fluorophenyl]-3,4,5,6-tetrahydropthalimide

4.60 g (15 millimoles) of N-(2-fluoro-4-chloro-5-formylphenyl)-3,4,5,6-tetrahydropthalimide and 6.30 g (16.5 millimoles) of carboethoxychloromethylenetriphenylphosphorane in 15 ml of ethanol are stirred at room temperature for 15 minutes. The mixture is then cooled to 0° C. and the precipitated product is filtered off.

Yield: 68%, mp.: 104–107° C.

20 N-[3-(1'-ethoxycarbonyl-1'-chloroethenyl)-4-chlorophenyl]-3,4,5,6-tetrahydropthalimide

30 651 g (2.25 moles) of N-(4-chloro-5-formylphenyl)-3,4,5,6-tetrahydropthalimide are introduced a little at a time into 956 g (2.5 moles) of carboethoxychloromethylenetriphenylphosphorane in 1.3 l of ethanol at 30° C. After the end of the addition, stirring is carried out for a further 30 minutes. The mixture is then cooled to -10° C. and the precipitated product (3) is filtered off.

35 Yield: 82%, mp.: 112–114° C.

Examples of use

The comparative agents used were I. N-phenyl-N'-(1,2,3-thiadiazol-5-yl)-urea and II. 6,7-dihydropyridol(1,2- α :2',1'- α)pyridilium as the dibromide monohydrate salt and the compounds III-VI from EP-A 207 894, which compounds are stated under Example C

EXAMPLE A

Young cotton plants (Delta Pine variety, development stage: 5-6 developed foliage leaves) were cultivated under greenhouse conditions (day/night temperature 23/16° C., relative humidity 50-70%) and the foliage was treated, until dripping wet, with aqueous formulations of the stated active ingredients. The converted amount of water was 1,000 l/ha. 12 days after application of the active ingredient, the number of dropped leaves and the degree of defoliation as a percentage of the control were stated. No dropping of leaves occurred in the untreated control plants.

Agent containing active ingredient No.	Converted application rate kg/ha	% defoliation
1.1	0.062	26
	0.125	61
	0.250	80
	0.062	67
	0.125	79
	0.250	89
1.26	0.062	55
	0.125	84
	0.250	89
	0.062	50
	0.125	70
	0.250	97
1.17	0.062	83
	0.125	31
	0.250	67
	0.062	13
	0.125	31
	0.250	67
2.5	0.062	11
	0.125	27
	0.250	50
	0.062	11
	0.125	27
	0.250	50
4.1	0.062	83
	0.125	31
	0.250	67
	0.062	13
	0.125	31
	0.250	67
Comparative agent I	0.062	13
	0.125	31
	0.250	67
	0.062	13
	0.125	31
	0.250	67
Comparative agent II	0.250	11
	0.500	27
	0.250	11
	0.500	27
	0.250	11
	0.500	27

The results from Example A show that the novel agents are clearly superior to the commercial active ingredients I and II and display their good action as defoliants even at relatively low temperatures.

EXAMPLE B

Young sunflower plants (Spanners Allzweck variety, stage of development: 3 developed foliage leaves) were cultivated under greenhouse conditions and the foliage was treated, until dripping wet, with aqueous formulations of the stated active ingredients. The converted amount of water was

39

1,000 l/ha. 3 days after application of the active ingredient, the degree of withering of the leaves (desiccation) was rated.

Agent containing active ingredient No.	Converted application rate kg/ha	Withering of leaves
Comparative agent II	2.5	+/++
	0.25	0.50
	1.00	++
	0.25	++/+++
	0.50	+/++
	1.00	+++

40

The results described show that the novel agent leads to withering (desiccation) of the leaves in sunflowers in a similar manner to the commercial agent II.

EXAMPLE C

Young cotton plants (Delta Pine variety, stage of development: 5–6 developed foliage leaves) were cultivated under green house conditions (day/night temperature 28/20° C., relative humidity 514 70%) and the foliage was treated, until dripping wet, with aqueous formulations of the stated active ingredients. The converted amount of water was 1,000 l/ha. 3 days after application of the active ingredient, the number of dropped leaves and the degree of defoliation as a percentage of the control were stated. No dropping of leaves occurred in the untreated control plants.

Agent containing active ingredient No.	Converted application rate kg/ha	% defoliation
1.1	0.125	100
	0.250	98
1.17	0.125	95
	0.250	100
2.5	0.125	97
	0.250	100
7.27	0.125	100

-continued

Agent containing active ingredient No.	Converted application rate kg/ha	% defoliation
	0.125 0.250	42 77

The results show that the novel agents are clearly superior to the comparative agents from EP-A-207 894, which are stated subsequently, and display their good action as defoliants at much lower application rates.

We claim:

1. A method for the dessication and abscission of plant organs, wherein an effective plant organ desiccating and abscising amount of a derivative of N-phenyl-3,4,5,6-tetrahydrophthalimide of the formula I

where

R is hydrogen, fluorine or chlorine,
A is group I-1, I-2 or I-3

wherein

R¹ is hydrogen, chlorine, bromine, cyano or C₁-C₆alkyl,

R² is hydrogen, C₁-C₈-alkyl, [C₁-C₈-alkenyl] C₂-C₈-alkenyl, C₂-C₄-alkynyl, C₁-C₄-alkoxy-C₁-C₄-alkyl, C₁-C₄-alkylthio-C₁-C₄-alkyl, or phenyl-C₁-C₃-alkyl [or phenyl which is unsubstituted or substituted by halogen],

R⁴ and R⁵ are each hydrogen or C₁-C₃-alkyl,

Q is oxygen or sulfur,

R⁷ is hydrogen, C₁-C₆-alkyl, C₁-C₆-alkoxyalkyl, C₁-C₆-alkylthioalkyl or C₅ or C₆-cycloalkyl, and

R¹³ is hydrogen or C₁-C₄-alkoxycarbonyl,

is applied to plants or their habitat.

2. A method as claimed in claim 1, wherein an N-phenyl-3,4,5,6-tetrahydrophthalimide of the formula I, where R is hydrogen and A is a group I-1

35

I-1

is applied.

45

3. A method as claimed in claim 1, wherein an N-phenyl-3,4,5,6-tetrahydrophthalimide of the formula I where R is hydrogen, A is a group I-1, Q is oxygen, R¹ is chlorine or bromine and R² is methyl or ethyl, is applied.

50

4. A method as claimed in claim 1, wherein from 0.001 to 5 kg/ha of the N-phenyl-3,4,5,6-tetrahydrophthalimide of the formula I as set forth in claim 1 is applied to plants or their habitat.

55

5. The method of claim 3 wherein R¹ is chlorine and R² is C₂H₅,

UNITED STATES PATENT AND TRADEMARK OFFICE
CERTIFICATE OF CORRECTION

PATENT NO. : RE 37,664 E
DATED : April 16, 2002
INVENTOR(S) : Grossmann et al.

Page 1 of 1

It is certified that error appears in the above-identified patent and that said Letters Patent is hereby corrected as shown below:

Title page,

Item [54], “N-PHENL” should be -- **N-PHENYL** --.

Column 41,

Lines 45-55, the “OR³” in the formulas should be -- OR⁷ --.

Column 42,

Line 18, delete “[C₁-C₈-alkenyl]”;

Lines 21-22, delete “[or phenyl which is unsubstituted or substituted by halogen]”;

Line 28, “C₁-C₄-alkoxycarbonyl” should be -- C₁-C₄-alkoxycarbonyl --.

Lines 56-57, the claim should not be italicized and should read:

-- 5. The method of claim 3 wherein R¹ is chlorine and R² is C₂H₅. --

Signed and Sealed this

Fourteenth Day of October, 2003

JAMES E. ROGAN
Director of the United States Patent and Trademark Office
